UNITED STATES PATENT OFFICE.

WILLIAM OTIS SHEPARD AND CHARLES WALTER CASON, SR., OF CAMDEN, NEW JERSEY.

UMBRELLA ATTACHMENT.

No. 873,099.

Specification of Letters Patent.

Patented Dec. 10, 1907.

Application filed April 7, 1906. Serial No. 310,499.

To all whom it may concern:

Be it known that we, WILLIAM O. SHEPARD and CHARLES W. CASON, Sr., citizens of the United States, residing at Camden, in the 5 county of Camden and State of New Jersey, have invented a new and useful Umbrella Attachment, of which the following is a specification.

This invention relates to devices for attachment to various articles for suspending or connecting the same, more particularly to umbrellas for suspending the same from a pocket flap, belt or girdle, or other portion of a garment, when not in use, to prevent displacement or loss of the article.

With these and other objects in view which will appear as the nature of the invention is better understood, the same consists in certain novel features of construction as 20 hereafter fully described and claimed.

In the accompanying drawings, forming a part of this specification, and in which corresponding parts are denoted by like designating characters, is illustrated the preferred 25 form of the embodiment of the invention capable of carrying the same into practical operation.

In the drawings thus employed:—Figure 1 is a view of an umbrella with the improved 30 device attached to its handle. Fig. 2 is a view of a portion of an umbrella handle enlarged, with the improved device in longitudinal section. Fig. 3 is a front elevation of the improved device, detached. Fig. 4 is a 35 view of the improved device arranged as a suspender clasp. Fig. 5 is a view of the improved device arranged as a belt clasp. Fig. 6 is a view of the improved device arranged as a cuff fastener or holder.

40 The improved device comprises a plate 10 of sheet metal and when formed as in Figs. 1, 2 and 3 is provided with screw or rivet apertures 11 at the ends, whereby the plate may be attached to the handle portion 12 of an 45 umbrella, and with an integral tongue 13 extending from one end thereof and provided with oppositely disposed concaved portions, said tongue having its sides converging toward the free end 14 and with the free end 50 also bent outwardly at the concaved portions, as indicated in Figs. 1 and 2.

The "root" portion 16 of the tongue is

thus materially wider than the other portions, so that the strength and resiliency is correspondingly increased, as will be obvious. 55

The tongue projects toward the "tip" end 15 of the umbrella and is in position to serve as an efficient means for temporarily suspending the latter from the pocket of the owner, or from a belt, girdle, or other portion 60 of a garment. Thus a person carrying the umbrella is furnished with a ready means for supporting the same while the hands are otherwise engaged, thereby avoiding danger of losing or misplacing the umbrella. The 65 tongue 13 also offers an efficient means for suspending a card, memorandum, price list, or other matter in convenient position for ready reference.

The plate 10 and its tongue 13 are "struck" 70 out from a single piece of metal and may be of any required size or of any suitable material.

Attention is here called to the fact that the free end of the tongue at the guide lip 14 is 75 formed with oppositely disposed depressions while the longitudinal edges of the tongue converge towards the base of the latter, thereby to form a relatively thin shank.

In Fig. 4 of the drawings there is illustrated 80 a modified form of the invention in which the device is arranged as a clasp for suspenders and similar articles, the tongue 13^a being struck up from the plate 10^a and normally disposed in a horizontal position while in 85 Fig. 5 the plate 10^b is shown arranged as a belt clasped and is provided with a pair of horizontally disposed tongues 13^b the deflected ends of which are extended in opposite directions. 90

In Fig. 6 the device is arranged as a cuff holder with two of the plates 10^c connected by an integral bar 17 and each provided with an up struck spring tongue 13^c similar to the tongues shown in Fig. 1 of the drawings. 95

Having thus described the invention, what is claimed is:—

As a new article of manufacture, a clip formed of a flat metal plate provided with an up struck spring clamping tongue having its 100 free end spaced from the plate and its terminal portion deflected laterally to form a guide lip, said tongue being curved laterally at its juncture with the plate and having its

opposite longitudinal edges formed with depressions disposed one on each side of the guide lip, that portion of the tongue between the depressions, and base thereof being inclined towards one end of the plate to form a relatively thin shank.

In testimony that we claim the foregoing

as our own, we have hereto affixed our signatures in the presence of two witnesses.

WILLIAM OTIS SHEPARD.

CHARLES WALTER CASON, SR.
